The ornamental design for a center throttle console, as shown and described.

DESCRIPTION

FIG. 1 is a forward view into an aircraft cockpit with seats removed showing our new design of a center throttle console;

FIG. 2 is a forward view into an aircraft cockpit with seats included showing the center throttle console of FIG. 1; FIG. 3 is a left perspective view of the center throttle console of FIG. 1;

FIG. 4 is a right perspective view of the center throttle console of FIG. 1;

FIG. 5 is a right side view of the center throttle console of FIG. 1;

FIG. 6 is a left side view of the center throttle console of FIG. 1; and,

FIG. 7 is a top view of the center throttle console of FIG. 1. The dash-dash broken lines illustrating the interior of an aircraft cockpit depict environmental structure which forms no part of the claimed design. The dash-dot broken lines showing cross-sectional cut indicators form no part of the claimed design. The dash-dot-dot broken lines between the center throttle console and the aircraft cockpit illustrate boundaries of the claimed design and form no part thereof. The dash-dot-dot broken lines illustrating symbolic break lines form no part of the claimed design.
